TYPE LINE TRIMMING MACHINE

Paul Flüger, Hamburg-Wandsbeck, Germany

Application July 7, 1939, Serial No. 283,305
In Germany July 23, 1938

6 Claims. (Cl. 90—25)

This invention relates to a machine for calibrating type lines produced on matrix line composing and type line casting machines.

Type lines produced by such machines cannot be properly assembled without special fitting, because they differ as to height and thickness, due to the construction of the known matrix line composing and type line casting machines, and possess, moreover, undesirable burr. It becomes therefore necessary in setting up matter composed in such lines to adjust them by means of interposed pieces of paper, but this operation takes up much time and is open to the further objection that the paper often works out from between the lines during printing and thereby spoils the print.

It is the object of the invention to eliminate these drawbacks by bringing type lines produced on machines of the kind mentioned after complete cooling to size in one operation by subsequent machining with the aid of stationary knives.

In a machine according to the invention for bringing type lines to size, the stationary knives are so arranged relative to one another that one of the knives removes the burr positioned laterally of the top of the plain face of the line, another one acts on the base of the line to insure uniform height and a third knife cuts the ribbed line face parallel to the bearing surface exactly to the typographical measure.

The invention is illustrated by way of example in the accompanying drawings, in which

Figure 1 is a front view of the machine;

Fig. 2, a top view, partly in section, of Fig. 1;

Fig. 3, a vertical cross section on the line 3—3, of Fig. 2;

Fig. 4, a cross section on the line 4—4, of Fig. 2; and

Figs. 5 and 6 show, respectively, in cross section on an enlarged scale, a type line in unfinished and finished condition.

A pile of lines Z' taken out of the receiving galley of a type-setting machine is placed on a transport table 1 in such manner that a slide 2 moved by a weight 3 presses the lines against a bearing or application surface 4, as shown in Fig. 2. The drivers 5 of a conveying chain 6 push the lines Z' along a guide path 7. Instead of a chain an endless band or a slide moved by an eccentric may be employed. The guide path 7 is provided with a rear jaw 8 and an upper covering bar 9, which are firmly secured to the base plate 10, and also with a front jaw 11 firmly connected with the rear jaw 8 and supporting

springily disposed pressure bars 12. The rear jaw 8 is fitted with a springy pressure bar 13 which abuts against the underside Z⁵ of the line Z'. The springiness of the pressure bars 12, 13 permits their adaptation to unevennesses of the line Z' and to press the latter against the stationary rear jaw 8 and the lower face 14 of the covering bar 9, as indicated in Fig. 4. The lines Z' are brought into the guide path 7 so that the top Z⁶ bears against the lower face 14 of the bar 9 and the plain face Z² against the inner face 7 of the jaw 8.

Each line Z' passed through the guide path 7 between the pressure bars 12, 13 is acted on by three knives 15, 16, 17. The knife 15 serves for removing the burr Z³, shown in Fig. 5, formed at the top Z⁶ below the character. The knife 17 works on the ribbed line face Z⁴, and the knife 16 is intended for operating on the underside Z⁵ to insure uniform height of the lines. The knife 17 trims the ribbed face Z⁴ parallel to its application face Z² to the exact typographical measure, which is of particular importance for the assembling of the matter.

It is possible of course to calibrate and trim also ribless lines in the same manner.

Having been gaged as described, the lines Z' slide behind the guide path 7 upon the inclined collecting table 18 and are pushed aside by a slide 19 to make room for the next batch. The slide 19 is arranged on a double lever 21 oscillatable at 20 by means of a shaft 22 and a cam disc 23. A displaceable stop 24 serves as abutment to prevent the finished lines from tilting. The lines Z' are assembled on the table 18 in the order fed to the table 1. Drive is effected by a pulley 25, though the machine can be actuated also by a hand wheel 26, particularly for accurate adjustment.

The machine according to the invention is preferably connected with a typesetting machine.

I claim:

1. In a type line trimming machine, a magazine for receiving untrimmed type lines and including a stop face, a guide extending from said magazine and having one side in alignment with said stop face, means to feed the type lines collectively toward said stop face to cause a type line to press against said face, means to feed the type lines successively through said guide as they are moved into engagement with said stop face, and a set of trimming knives positioned to engage both sides and the bottom of each type line as it is moved along the guide.

2. In a type line trimming machine, a maga-

- zine for receiving untrimmed type lines and including a stop face, a guide extending from said magazine and having one side in alinement with said stop face, means to feed the type lines collectively toward said stop face to cause a type line to press against said face, means to feed the type lines successively through said guide as they are moved into engagement with said stop face, a set of trimming knives positioned to engage both 10 sides and the bottom of each type line as it is moved along the guide, a collecting table at the end of the guide and receiving the type lines from said guide, and means associated with said table effecting assembling of the type lines on the 15 table in side by side relation.
3. In a type line trimming machine, a magazine for receiving untrimmed type lines and including a stop face, a guide extending from said magazine and having one side in alinement with 20 said stop face, means to feed the type lines collectively toward said stop face to cause a type line to press against said face, means to feed the type lines successively through said guide as they are moved into engagement with said stop face, a 25 set of trimming knives positioned to engage both sides and the bottom of each type line as it is moved along the guide, a collecting table at the end of the guide and receiving the type lines from said guide, means associated with said table effecting assembling of the type lines on the 30 table in side by side relation, and driving means actuating the last mentioned means and operating the means for feeding the type lines through the 35 guide.
4. In a type line trimming machine, a magazine for receiving a row of untrimmed type lines in side by side relation and including a stop face, a guide extending from said magazine and having a fixed side alined with the stop face, said guide 40 further having a fixed side against which the type faces of the type lines may bear and a pair of spring pressed sides urging the type lines against the fixed sides of the guide, means to feed the type lines collectively toward said stop face to cause the end type line of the row to engage against said stop face, means to feed the type lines successively from engagement with the stop 45 face through the guide, and a set of trimming knives positioned to engage both sides and the

bottom of the type lines as they are fed through the guide.

5. In a type line trimming machine, a magazine for receiving a row of untrimmed type lines in side by side relation and including a stop face, 5 a guide extending from said magazine and having a fixed side alined with the stop face, said guide further having a fixed side against which the type faces of the type lines may bear and a pair of spring pressed sides urging the type lines 10 against the fixed sides of the guide, means to feed the type lines collectively toward said stop face to cause the end type line of the row to engage against said stop face, means to feed the type lines successively from engagement with 15 the stop face through the guide, a set of trimming knives positioned to engage both sides and the bottom of the type lines as they are fed through the guide, a collecting table at the end of the 20 guide and receiving the type lines from said guide, and means associated with said table effecting assembling of the type lines on the table in side by side relation.
6. In a type line trimming machine, a magazine for receiving a row of untrimmed type lines 25 in side by side relation and including a stop face, a guide extending from said magazine and having a fixed side alined with the stop face, said guide further having a fixed side against which the type faces of the type lines may bear and a 30 pair of spring pressed sides urging the type lines against the fixed sides of the guide, means to feed the type lines collectively toward said stop face to cause the end type line of the row to engage against said stop face, means to feed the 35 type lines successively from engagement with the stop face through the guide, a set of trimming knives positioned to engage both sides and the bottom of the type lines as they are fed through the guide, a collecting table at the end 40 of the guide and receiving the type lines from said guide, means associated with said table effecting assembling of the type lines on the table in side by side relation, and driving means actuating the last mentioned means and operating the 45 means for feeding the type lines through the guide.

PAUL FLÜGER.
